In Belgium January 17, 1950

7 Claims. (Cl. 74—471)

1

The present invention relates to switches controlled by bars actuated in various combinations, hereafter designated as code bar switches and which can be used, for instance, in telephone systems. Its object is to realize a switch of this type occupying the minimum amount of space which is allowed for a satisfactory performance and utilizing economical, reliable and easily manufactured components.

A feature of the invention resides in a code bar switch comprising a set of parallel code bars and a set of selection levers, the latter arranged perpendicularly to the former and such that they can pivot about a line perpendicular to the code bars.

Another feature of the invention resides in the fact that each selection lever comprises two main parts, both perpendicular to the code bars, the first being pivoted at both ends in a fixed part, to provide fulcrums for the selection levers, the second being made integral with the first by means of a bridged part, and being provided at both ends with two actuating arms which may actuate any desired mechanism such, for instance, as a two-position device.

Yet another feature of the invention resides in said bridged part comprising two rigid arms joining said first and second main parts, and bent in such a way that they are interleaved in the narrow spaces which remain between the parallel code bars, so as to limit the volume of the complete arrangement.

Yet another feature of the invention resides in the fact that each of said selection levers including said bridged part can be cut from a flat plate and that they have all the same shape and dimensions, said arms pertaining to said bridged part being bent perpendicularly to said flat plate either in one sense or in the other, in order to obtain two kinds of selection levers which can be intermeshed so as to limit the space occupied by the complete arrangement.

Code bar switches are well known. They generally comprise a set of so-called code bars which are located parallel to one another and which are all provided with slots, or openings, or lugs, etc., at various points along their length, so that for particular positions of the code bars, which can all be shifted along their length, at one particular point, the said slots, or openings, or lugs, will be aligned and can thus actuate some pre-selected devices.

It will be readily seen that if the number of code bars is n and the number of positions which each code bar can occupy is denoted by p , the

2

total number of combinations c which can be obtained, or the total number of different actuating parts which can be operated in response to various combinations, will be given by $c=p^n$. Accordingly, the number of combinations can be very large for a small number of code bars. In most cases, however, the code bars will be operated by magnets and accordingly, a binary scale with $p=2$ will be used.

It should be realized that the use of switches and more particularly multi-switches operated on the code bar principle, can be very valuable indeed, in telephone systems wherein numbers are frequently signalled in some form of binary scale or other scales which are different from the decimal scale. Accordingly, the use of a code bar switch operated on the same scale as that which is used for electrical signalling will make some translations from one scale to another unnecessary.

Other features and objects of the present invention will appear from the following description of an embodiment, given as a non-limitative example, with reference to the appended drawings which represent:

Fig. 1, a plan view of the code bar arrangement;
Fig. 2, a side view of Fig. 1;

Fig. 3, a cross-sectional side view of Fig. 1 along the line $x-x'$;

Fig. 4, a cross-sectional side view of Fig. 1 along the line $x-x'$, a particular combination of code bars having been actuated resulting in the operation of a particular lever;

Fig. 5, a cross-sectional end view of Fig. 1, along the line $y-y'$;

Fig. 6, a cross-sectional end view of Fig. 1 along the line $z-z'$.

The code bar arrangement which is shown in the various figures utilizes five code bars which can each occupy two different positions in accordance with the electrical condition of the magnet (not shown) controlling each code bar. Accordingly, thirty-two combinations are possible and a number of selection levers equal to or less than thirty-two can be used.

Referring to Fig. 1, a frame 1 having a U-shaped cross section is shown. At regular intervals along its length, the bottom part of the frame 1 is cut along a line perpendicular to its length and also along two lines parallel to its length along both vertical sides, in order to obtain a small rectangular part such as 2 which can be bent upwards along a plane perpendicular to the bottom part of the frame. This rectangular part is provided with a series of five slots such as 3, 4,

5, 6, and 7 (Fig. 5) in which the various code bars 8, 9, 10, 11 and 12 are free to slide from one position to another, each under the control of a corresponding magnet (not shown) and its associated mechanical parts such as its armature and restoring springs (not shown). These auxiliary parts have not been shown since they are of conventional design and are well known to those skilled in the art.

Considering Fig. 1, as well as Figs. 3 and 4, 10 it will be seen that each of the code bars 8, 9, 10, 11 and 12 is provided with a series of slots 14 . . . 38 such as 13, the shape of which can be seen more clearly on Figs. 3 and 4. These slots such as 13 have substantially the shape of 15 a right angle trapezium.

A series of selection levers such as 39 are provided, each comprising two parts such as 40 and 41 which are both perpendicular to the code bar such as 8 and which are united by a bridged part 20 comprising two arms such as 42 and 43 which have been bent so as to be perpendicular to the plane containing the parts such as 40 and 41, and which are inserted between the various code bars so as to reduce the space taken by the complete mechanism, e. g., arm 42 is inserted between code bars 10 and 11 and arm 43 is inserted between code bar 8 and one vertical side of the frame 1. It will be seen that the part 41 of the selection lever 39 is further provided with two symmetrical arms 44 and 45 at both ends. The ends of both the arms 44 and 45 are bent in order to provide actuating parts 46 and 47 which can operate any desired mechanism such, for instance, as a two-position device. The ends of the part 41 are further provided with small holes 48 and 49 in which two springs 50 and 51 are attached. The other ends of these springs 50 and 51 are held in holes such as 52 provided in L-shaped pieces 53 and 54 which are secured to the frame 1. The middle right-hand portion 55 of the part 41 has been bent perpendicularly to the plane of Fig. 1 and can be seen more clearly on Figs. 3 and 4.

The ends of the part #8 of the selection lever 39 have been provided with two lugs 56 and 57 which are inserted in small rectangular openings provided in the vertical sides of the L-shaped pieces 53 and 54. Slots such as 58 and 59 have also been cut in the vertical sides of the frame 1 to permit the insertion of the lugs 56 and 57.

It will be appreciated that the levers such as 39 are so shaped and so designed that they can be intermeshed between one another in a horizontal plane so as to use a minimum amount of space. Also, all the levers have the same shape which is obviously of very great advantage from a production point of view. In order to obtain the desired intermeshing between the selection levers themselves and also between the arms such as 42 and 43 and the various code bars 8 . . . 12, it is merely necessary that the arms such as 42 and 43 should be bent perpendicularly to the main plane of the levers, either in one sense or the other, e. g. levers 39 and 61 are completely identical as shown on Fig. 1 and lever 39 only differs from lever 60 by the sense in which the arms such as 42 and 43 are bent.

Considering the various selection levers such as 39 which are pivoted by means of their lugs such as 56 and 57, it will be seen that the bent part 55 of selection lever 39 is normally resting at least on one of the code bars such as 6 (Fig. 3). In fact, for all the selection levers such as 39 which have been shown, only one code bar is used as a resting point for the part such as 55. This is,

of course, solely dependent upon the particular combination of operated and non-operated code bars, which is necessary to actuate one particular lever, but it will be recognized that for all selection levers such as 39, including those not shown on the drawing, at least three resting points are provided when the lever is not actuated, e. g. for lever 39, the two small rectangular openings corresponding with lugs 56 and 57 and the code bar 8.

Considering now the operation of mechanism, it will be assumed that it is desired to actuate selection lever 39. Since the bent part 55 of the selection lever 39 is resting upon the code bar 8, but could be moved under the action of the springs 50 and 51 in the slots 13, 23, 28, and 33 respectively, provided in the code bars 9, 10, 11 and 12, the particular combination which is necessary for the operation of the selection lever 39 will be denoted by 10000, indicating that the code bar 8 must be operated in the direction of the arrow f_1 (Fig. 4), while the remaining bars 9, 10, 11 and 12 remain in the position shown. As soon as the code bar 8 is pushed in the direction of the arrow f_1 , slot 13 will come underneath the bent part 55 and, as shown on Fig. 4, all the slots 13, 18, 23, 28 and 33 will be in alignment and accordingly, both the springs 50 and 51 will pull the selection lever 39 downwards and part 55 will slide down the inclined surface of the right angle trapezium 13 under the tension of the aforementioned springs. The latter will rotate clockwise into small rectangular openings provided in the L-shaped parts 53 and 54 and the bent part 55 will be arrested at the bottom of the five slots 13, 18, 23, 28 and 33. The arms 44 and 45 of the selection lever 39 will also be rotated and accordingly the bent ends 46 and 47 of these arms will travel along a distance which is sufficient to operate any desired mechanism, which, for instance, may comprise any known two-position device (not shown). Upon retraction of an actuated code bar, the bent part 55 of an actuated selection lever 39 operates in reverse direction due to its travel up the inclined surface of the right angle trapezium 13 to assume its original position as will be obvious from an examination of Figs. 3 and 4. It will be understood that if any of the other coded bars 14 . . . 38 are moved, and the necessary five corresponding slots in alignment, that the same action will take place.

The operation of the other levers shown on the figure, as well as those not shown, will proceed along similar lines, the combinations for the remaining four levers shown, i. e. 58, 61, 62 and 63, being respectively: 01000 (code bar 9 operated), 00100 (code bar 10 operated), 00010 (code bar 11 operated) and 00001 (code bar 12 operated).

60 Cross pieces such as 64 can be provided at both ends of the frame 1 in order to guide the code bars such as 3. Rectangular slots such as 65 and 66 have also been provided respectively in the main frame 1 and in the L-shaped part 54 in order to allow the displacement of the selection levers such as 39. Similar slots 67 and 68 are respectively provided in the other side of the frame and in the L-shaped part 53.

The end view shown on Fig. 5 is self-explanatory and clearly shows the manner in which the various code bars are guided in the bent part 2 of the frame 1.

Referring now to Fig. 6, this shows the manner in which the various code bars are further guided along their length. Due to the interleaving of

the arms such as 42 and 43 between the various code bars and the vertical sides of the frame 1, it is not possible to provide a guiding bent piece such as 2 at intermediate points along the length of the code bars. As can be seen from Fig. 6 as well as from Fig. 1, at intermediate points, prongs such as 69 and 70 have been cut in the bottom part of the frame 1 and bent upwards in a vertical plane. On the other hand, a second set of prongs such as 71, 72, 73 and 74 have also been cut and bent in a similar manner but are aligned at a certain distance from the first two prongs 69 and 70. This staggering permits the insertion of the arms such as 42 and 43 pertaining to the selection levers (not shown) which immediately follow selection lever 63.

These staggered prongs such as 69 will provide adequate guidance for the code bars e. g. code bar 8 is guided between prong 69 and prong 71, code bar 9 is guided between prong 71 and prong 72 etc. Pins 75 and 76 located perpendicularly to the various code bars are used to support them.

It will be readily recognized that although the embodiment shown refers to a set of five code bars which can each be placed in two different positions, the principles of the present invention can also be applied to a code bar arrangement in which a different number of code bars are provided, each being able to occupy two or more different positions.

While the principles of this invention have been described above in connection with specific apparatus, it is to be clearly understood that this description has only been made by way of example and not as a limitation on the scope of the invention.

I claim:

1. Code bar mechanism comprising a fixed frame member, a plurality of spaced parallel code bars arranged for displacement in a certain plane, a plurality of selection levers cooperatively associated with said code bars, each of said levers comprising two separated main portions, each portion being perpendicular to said code bars, one of said portions being pivotally mounted on said frame member, the other of said portions having a first part adapted to cooperate with said code bars, bridging means for connecting both of said portions together, each of said means extending substantially parallel with and interleaved among said code bars, each of said means in staggered relationship with the other, whereby to permit close disposition of said selection levers, each of said other portions having an actuation part.

2. Code bar mechanism comprising a fixed frame member, a plurality of parallel code bars arranged for relative parallel displacement, a plurality of selection levers each of said selection levers comprising a portion arranged for pivotal movement about an axis substantially perpendicular to said code bars and parallel to the plane of movement thereof and a second portion spaced from said first portion by a distance sufficient to accommodate a first portion of a second lever and a second portion of a third lever therebetween, means bridging said portions to permit said second portion to pivot about said axis each of said bridging means extending substantially parallel with and between different of said code bars, said second portion including means cooperating with said code bars to permit movement of said second portion about said axis in accordance with a predetermined positional relationship among said code bars, and biasing means for biasing said last

named means into cooperative relationship with said code bars.

3. In a mechanism actuated by a plurality of code bars arranged for relative parallel displacement, a plurality of levers arranged for selective operation in accordance with predetermined positional relationship between said code bars, each lever comprising a first portion, a second portion and a bridging portion mechanically bridging said first and second portions, said first and second portions being spaced in the direction of the code bars by a distance sufficient to accommodate a first portion of a second lever and a second portion of a third lever therebetween, each said bridging portion being arranged to extend substantially parallel with said code bars, different of said bridging portions extending substantially parallel with and between different of said code bars, one of said first and second portions including means adapted to cooperate with said code bars to permit movement of said one portion in accordance with an arranged permutation among said code bars, means associated with each of said levers for urging such movement by said one portion and means for pivotally mounting the other portion about an axis substantially perpendicular to said code bars.

4. In a code bar system wherein a plurality of parallel code bars having detents adapted to be arranged in permutation, and wherein said bars are arranged for relative parallel displacement in a common plane, a lever assembly comprising spaced first and second portions and a bridging portion mechanically interconnecting said first and second portions, said first portion including means for pivoting said assembly about an axis substantially perpendicular to the direction of movement of said code bars, said first and second portions being spaced by a sufficient distance to accommodate a corresponding first portion of a second lever assembly and a corresponding second portion of a third lever assembly therebetween, each of said bridging portions extending substantially parallel with and between different of said code bars in staggered relation, means associated with said second portion for cooperating with detents in the code bars to permit movement of said second portion upon a predetermined permutation among the code bars, and means for urging such movement.

5. In a code bar system, the combination in accordance with claim 4 in which said second portion of each assembly is provided with a pair of actuating arms rigidly affixed thereto and extending therefrom.

6. In a code bar system, the combination in accordance with claim 4 in which said bridging portion comprises two parallel rigid arms joining said first and second portions and at least one of said arms being interleaved in a space between two of the parallel code bars.

7. In a code bar system, the combination in accordance with claim 4 in which said first and second portions comprise flat plates, said plates being arranged in a common plane.

GEORGES XAVIER LENS.
